LOUIS EUGÈNE FRIDERICH, OF PARIS, FRANCE, ASSIGNOR TO LA SOCIÉTÉ FERDINAND GROS ET BOUCHARDY, OF PARIS, FRANCE.

PROCESS FOR THE PRODUCTION OF CYANAMIDS.

1,371,616.

Specification of Letters Patent.

Patented Mar. 15, 1921.

Application filed October 17, 1918. Serial No. 258,658.

To all whom it may concern:

Be it known that I, LOUIS EUGÈNE FRIDERICH, citizen of the Republic of Switzerland, and resident of Paris, France, (post-office address, 4 Rue Girardon,) have invented a new and useful Process for the Production of Cyanamids, which is fully set forth in the following specification.

This invention relates to the formation of cyanamid from calcium carbid and nitrogen; and its object, briefly stated, is the provision of an improved process which may be carried out more rapidly and with larger resultant yields than is possible with the processes heretofore in use.

According to the invention, powdered carbid is deposited in boxes which are introduced successively into, and are advanced automatically through, a suitable tunnel furnace, during which time they are heated and subjected to the action of the nitrogen, the arrangement being such that the reaction, which is exothermic, is completed by the time the boxes reach the discharge end 25 of the furnace. The boxes utilized are comparatively large and shallow, and the carbid is loosely deposited therein in thin layers, in order to expose to the heat as large as possible a surface in proportion to the volume treated. The carbid is quickly raised to the reaction temperature; but before such temperature is reached, the nitrogen, which is caused to flow through the furnace in a direction opposite to that traveled by the carbid boxes, has obtained free access to the carbid, the originally pulverulent mass sintering into a compact mass or body during the reaction. The cyanamid is cooled as quickly as possible after its formation; but this rapid cooling, however, is of less importance than the rapid heating, for the reason that decomposition takes place most rapidly when the material is in powdered form, which is the case during heating.

45 The accompanying drawings show one form of furnace in which the present process may be carried out, and in said drawings:

Figures 1, 1^A and 1^B constitute a longitudinal vertical section of the furnace;

Figs. 2 and 3 are transverse vertical sections on lines 2—2 and 3—3, of Figs. 1 and 1^A, respectively.

Referring more particularly to the drawings, the tunnel furnace therein represented

is constructed with a floor which comprises two fixed sections or parts 1, 1, spaced apart from each other to receive between them a central, longitudinal beam 2 covered with refractory material. This beam 2 is adapted to be raised and lowered by means of pairs of eccentrics 4 through the intermediary of transverse beams 3, the eccentrics being operated by suitable shafting 17. The eccentrics are provided with annular straps or collars 4' wherein they rotate, the straps of one pair of eccentrics being rigidly connected at their tops with the adjacent transverse beam 3, as indicated at 4², while the tops of the remaining pairs of straps are hinged as at 4³ to the corresponding transverse beams. The eccentrics are represented in the drawings as at the top of their stroke, so that the cross-beams 3 and, hence, the central beam 2, occupy a raised position, 75 with the latter beam projecting above the surface of the floor; but in the normal position of parts, the eccentrics are lowered, and with them the beams 3 and 2, the upper surface of the beam 2 lying below that of the floor, so that the carbid boxes 100 rest upon and are supported by the floor. At each revolution of the eccentrics, the aforementioned beams are lifted as above explained, with the result that the boxes are 80 picked up by the central beam and raised above the floor; then, as the rotation of the eccentrics continues, the central beam, together with the boxes, will be moved in a forward direction through the furnace, it 85 being understood that the boxes are loaded one after another upon the beam in some suitable manner; finally, the eccentrics start their downward movement, thereby lowering and moving back the central beam 90 which, in turn, deposits the boxes upon the floor, the cycle of movements continuing 95 during the working of the furnace.

Tight joints between the furnace and the pit wherein the operating mechanism is arranged are effected by means of fixed iron sheeting 5 located beneath the cross-beams, and of leather bellows-like sheets 6 fixed to the upper surfaces of said beams and to the side walls of the furnace. To avoid the entry of air into the furnace during the charging of the boxes containing the powdered carbid, and the removal of the boxes containing the cyanamid, two gas locks 7 and 8 are provided at the delivery and discharge 110

ends respectively of the furnace and constitute extensions of the furnace, these locks being isolated from the furnace by air-tight gates 10 and 9'.

5 Considering now the actual process itself, the furnace is first heated to a high temperature by means of suitably-arranged carbon electrodes 11, one of which is indicated, the temperature being regulated during the operation by cutting out of the circuit the proper number of carbons. Once the required temperature is reached, the gates are closed and nitrogen is introduced into the furnace through the inlets 15. The cover 12
10 of the lock chamber 7 is then raised, and a box 100 containing the carbide is deposited in said chamber, after which the cover is put back and nitrogen is admitted to the lock chamber to expel the air. The gate 10
15 is then raised by means of a system of counter weights 13 (which is also utilized to raise and lower the lock chamber cover, as will be understood from the dotted-line showing in Figs. 1 and 1^B), and the box is
20 finally forced into the furnace proper by the plunger mechanism 14. Thereupon the furnace gate 10 is closed again and a fresh box of carbide deposited in the lock chamber. The feeding mechanism comprising the eccen-
25 trics 4 and their operating shaft is then set in motion, and its speed regulated in any desired manner. Removal of the boxes containing the cyanamid takes place at the opposite end of the furnace, as will be understood,
30 the withdrawal of the boxes from the lock chamber 8 being effected by a second plunger mechanism 14 which is similar to the charging mechanism 14, and the manipulation of the cover 12' and gate 9' by a counter-
35 weight mechanism 13' similar to the mechanism 13 previously mentioned.
40

Safety valves 16 are preferably utilized to permit the escape of any explosive gases which may be formed as a result of faulty working, these valves being arranged in the roof of the furnace.

During the course of the operation, the nitrogen travels through the furnace in the opposite direction from the carbid boxes,

and a suitable exit is provided for the escape 50 of any nitrogen which may be left after it has completed its traverse of the boxes; but in general the amount of nitrogen used is such as will be completely absorbed by the carbid. It will be seen that the electrodes 55 11 are located only in the inlet portion or zone of the furnace, and are grouped comparatively close together adjacent the charging lock chamber, but are spaced farther and farther apart as they approach the central 60 portion of the oven where the second zone commences. The action of the electrodes is, of course, to highly heat the walls of the furnace, particularly the roof, the heating of the carbid being effected by radiation from 65 said walls. In this way, the transformation of the carbid into cyanamid takes place rapidly, the crust of cyanamid initially formed cracking and allowing access to the underlying carbid. Cooling takes place in the sec- 70 ond half or zone of the furnace, and is rapidly effected, because of the fact that the progressive heating of the carbid is effected only at the rate at which it enters into re- 75 action;—that is to say, the reaction heat is transmitted layer by layer through the car- bid, each successive layer cooling while the layers beneath it are reacting.

What I claim as new and desire to secure by Letters Patent of the United States is:— 80

A process for the production of calcium cyanamid, consisting in inserting a charge of powdered calcium carbid into a furnace; heating solely the upper layer of the charge to reaction temperature, and permitting such temperature to be transmitted exothermically from layer to layer down to the bottom layer; and moving the charge progressively through the furnace against a current of nitrogen in such a manner that immediately the said upper layer has become converted into cyanamid the charge will have reached a cool zone of the furnace, so that such layer will be cooled while the successive layers below it are reacting layer by layer. 95

In testimony whereof I have signed this specification.

LOUIS EUGÈNE FRIDERICH.
